(57) **CLAIM**

We claim the ornamental design for a suction tool connector, as shown and described.

DESCRIPTION

FIG. 1 is a front perspective view of a suction tool connector, showing our new design;

FIG. 2 is an enlarged right side elevation view thereof;

FIG. 3 is an enlarged front elevation view thereof;

FIG. 4 is an enlarged left side elevation view thereof;

FIG. 5 is an enlarged back elevation view thereof;

FIG. 6 is an enlarged top plan view thereof; and,

FIG. 7 is an enlarged back perspective view thereof.

The broken lines depict portions of the suction tool connector that form no part of the claim.
